(57) **CLAIM**

The ornamental design for a speakerphone, as shown and described.

DESCRIPTION

This application is a reissue divisional application of U.S. Design application Ser. No. 29/620,772, now U.S. Design Pat. No. RE46,940, which issued on Jun. 20, 2018 and is a reissue of U.S. Design Pat. No. D760,201, which issued on Jun. 28, 2016 from U.S. Design application Ser. No. 29/518, 227, filed on Feb. 20, 2015, the contents of which applications are entirely incorporated by reference herein.

FIG. 1 is a perspective view showing a top, a front, and a left side of a speakerphone according to our new design; FIG. 2 is an elevational view of the front of the speakerphone;

FIG. 3 is an elevational view of a back of the speakerphone; FIG. 4 is an elevational view of the left side of the speakerphone;

FIG. 5 is an elevational view of a right side of the speakerphone; and

FIG. 6 is a plan view of the top of the speakerphone; and, FIG. 7 is a plan view of a bottom of the speakerphone.

The broken lines showing in FIGS. [1-5 and 7] 1-7 are for illustrative purposes only and form no part of the claimed design.
